UNITED STATES PATENT OFFICE.

ALFRED TURENNE NEWELL, OF BIRMINGHAM, ALABAMA.

ASPHALT SPREADER.

Application filed March 14, 1927. Serial No. 175,338.

My invention relates to a machine for spreading asphalt or the like material on roadways in a condition ready for the rolling operation and it is an object of the invention to provide a machine of this character which will eliminate a large amount of manual labor in the laying of roadways and by means of which such operation may be more quickly, easily and more efficiently accomplished at a reduced cost, all as will be hereinafter more particularly described and claimed.

Referring to the accompanying drawings, which are made a part hereof and on which similar reference characters indicate similar parts,

Figure 1 is a diagrammatic view illustrating one application of my invention,

Figure 2, a side elevation,

Figure 3, a vertical longitudinal section,

Figure 4, a top plan view,

Figure 5, a diagrammatic front elevation,

Figure 6, a fragmentary rear elevation, and

Figure 7, a diagrammatic plan view.

In the drawings reference character 10 indicates the flanged wheels supported upon steel rails 11 at each side of the roadway. The flanged wheels on each rail are carried by trucks which comprise inner and outer side plates 12 and 13 connected by spacing members 14. The trucks are connected by means of braces 15 which extend across the roadway and upon which are supported the various blades and the like of the machine.

The machine is designed to scrape over the roadway in order to properly level and form the same into shape and for this purpose I provide a cutting blade or scraper 16 secured to the lower portion of a plate 17 which extends transversely across the machine, such plate being adjustably mounted at its ends between angle irons 18 and by means of screws 19 can be raised or lowered as desired.

The scraper or cutting blade 16 preferably conforms to the arc or crown of the roadway and is provided at its extremities with cutting blades or points 20 (Figures 3 and 5) of any desired shape for channeling out the sides of the roadway where it is desirable to provide thicker edges for insuring greater wearing qualities. The cutting blades or plates 20 preferably taper one inch for each four inches of its length.

Rearwardly of the cutting blade 16 is carried a pivotally mounted pan or apron 21 upon which is adapted to be dumped from

trucks or the like the ready mixed asphalt or other preparation of which the roadway is to be formed and such preparation is preferably dumped in small spaced piles on such pan or apron and is raked therefrom onto the sub-grade or surface of the roadway prepared by the cutting blade or scraper 16. On account of the spreader or apron 21 having its lower portion in contact with the surface of the roadway prepared by the cutting blade 16 such spreader or apron will form a drag and will serve to smooth down the sub-grade or surface of the roadway so that rolling is unnecessary. Also by depositing the material on the spreader or apron the standard specifications for road building which require the asphalt composition or the like be not dumped directly on the sub-grade is adequately complied with and the weight of the deposited material serves to hold down the apron.

Rearwardly of the apron 21 is supported, in a manner similar to the blade 16, an adjustably mounted blade or rake 22 which is adapted to strike off, screed or comb the road building composition. Also adjacent the rear of the machine is a similar adjustably mounted blade or gage 23 for determining the final thickness of the spread material.

A longitudinally disposed platform 24 may be provided at each side of the machine across which is adapted to be suspended one or more platforms 25 for supporting laborers for raking the material from the apron onto the roadway.

At the rear end of the machine in spaced relation to the blade 23 is a cross member 26 connected by braces 27 with a bar 28 both of which members 26 and 27 are vertically adjustable in a manner similar to the blade 16.

The machine may be provided with its own power plant by means of which it may be propelled or it may be pulled by a tractor or power unit ahead of the same, as shown. When the machine is pulled by a tractor or the like I preferably provide a flexible bridle 29 which comprises a pair of straps which have their front ends connected and have their rear ends attached to the trucks at the sides of the roadway, such flexible straps are adapted to lie flat on the ground to permit trucks or other vehicles to back in and discharge their loads without interference.

In lieu of the flanged wheels, which are supported on the spaced rails at each side of the roadway, obviously, other wheels may be provided which operate directly on the road-

way without the use of rails, thus permitting the spreading of material on any width streets or city pavements for resurfacing the same.

5 It will be obvious to those skilled in the art that various changes may be made in my device without departing from the spirit of the invention and therefore I do not limit myself to what is shown in the drawings and 10 described in the specification, but only as indicated in the appended claims.

Having thus fully described my said invention, what I claim as new and desire to secure by Letters Patent, is:

15 1. A machine for use in roadbuilding comprising a scraper adapted to scrape off the surface of the roadway, an apron for receiving material to be deposited on the roadway said apron forming a drag for smoothing 20 the surface operated upon by the scraper, and means for striking off and leveling the material deposited from the apron, substantially as set forth.

25 2. A spreading machine for use in roadbuilding comprising a frame, means at each side of the frame for supporting the same, a scraper at the forward end of the machine, a material receiving apron disposed behind said scraper adapted to have material 30 dumped thereon to be deposited on the roadway and forming a drag, and means carried by said frame behind said apron for striking off and leveling the material deposited from the apron, substantially as set forth.

35 3. The combination in a machine for building roadways, of a frame, a vertically adjustable blade suspended at the forward end of the frame said blade having a cutting edge shaped to plane or screed the roadway, 40 an apron supported behind said cutting edge and adapted to receive material from which the roadway is formed said apron forming a drag for smoothing the surface upon which the material is subsequently deposited, a 45 transversely suspended vertically adjustable blade behind said apron adapted to strike off the material deposited from the apron, and an additional vertical plate disposed transversely of the machine behind said last- 50 mentioned plate for regulating the exact thickness of the material deposited from the apron, substantially as set forth.

55 4. A machine for use in roadbuilding comprising a frame, means disposed at each side of the frame for supporting the same, a transversely disposed vertically adjustable scraper at the forward end of the machine adapted to scrape off the surface of the roadway, an apron for receiving material to be deposited 60 on the roadway said apron being pivotally

supported behind said scraper and forming a drag for smoothing the surface operated upon by the scraper, a transversely disposed vertically adjustable blade mounted in spaced relation behind the apron for striking off the material deposited therefrom, and an additional blade disposed rearwardly of the last-mentioned blade for determining the thickness of the roadway, substantially as set forth. 65

5. A machine for use in road building comprising a scraper adapted to scrape off the surface of the roadway in advance of the machine, means for adjusting either end of said scraper, an apron for receiving material to be deposited on the roadway, said apron forming a drag for smoothing the surface operated upon by the scraper, and means for striking off and leveling the material deposited from the apron the said means being adjustable at either side to form a level or a 80 sloping road surface, substantially as set forth.

6. A road building machine comprising a frame, means at each side of the frame for supporting the same, a scraper at the forward end of the frame for scraping off the surface over which the machine passes, an apron disposed behind said scraper for receiving material from which the roadway is formed, said apron forming a drag for smoothing and packing the surface operated upon by the scraper, and a template mounted in spaced relation behind the apron for striking off the material deposited therefrom, and for determining the thickness and curvature 90 of the material, substantially as set forth. 95

7. A road building machine comprising a frame, means at each side of the frame for supporting the same, a scraper at the forward end of the frame for scraping off the surface over which the machine passes, a cutting blade mounted at each end of the scraper for channelling out a trench for receiving material to form a curb, an apron disposed behind said scraper for receiving material from which the roadway is formed, said apron forming a drag for smoothing and packing the surface operated upon by the scraper, a template mounted in spaced relation behind the apron for striking off the material deposited therefrom and for determining the thickness and curvature of the material, and a platform mounted across the frame for supporting laborers for raking the material from the apron, substantially as set forth. 100 105 110 115

In witness whereof, I have hereunto set my hand at Savannah, Chatham Co., Georgia, this 10th day of March, A. D. nineteen hundred and twenty-seven.

ALFRED TURENNE NEWELL.
